United States Patent

Des. 241,013
Patented Aug. 17, 1976

241,013

BOTTLE OR THE LIKE

Evert Jan Dekker, Voorburg, Netherlands, assignor to Indola Cosmetics B.V., Rijswijk (Z.H.), Netherlands

Filed Feb. 4, 1975, Ser. No. 546,892

Term of patent 14 years

Int. Cl. D9—01

U.S. Cl. D9—160

FIG. 1

FIG. 3

FIG. 2

FIG. 1 is a top plan view of a bottle or the like showing my new design;

FIG. 2 is an elevational view, the sides not shown being the same in appearance as the side shown; and

FIG. 3 is an exploded perspective view thereof.

I claim:

The ornamental design for a bottle or the like, as shown and described.
